UNITED STATES PATENT OFFICE.

GRANVILLE O. RHODES, OF HUNTINGTON, WEST VIRGINIA.

BARREL TRUCK AND RACK.

Application filed June 19, 1922. Serial No. 569,190.

To all whom it may concern:

Be it known that I, GRANVILLE O. RHODES, a citizen of the United States, residing at Huntington, in the county of Cabell and State of West Virginia, have invented certain new and useful Improvements in Barrel Trucks and Racks, of which the following is a specification.

This invention relates to combined barrel trucks and supporting racks, and has for one of its objects to improve the construction and increase the efficiency and utility of devices of this character.

Another object of the invention is to provide a device of this character which may be disposed beneath a barrel when the latter is in horizontal position without lifting or otherwise moving the barrel until the truck is in condition to be tilted to elevate the barrel.

Another object of the invention is to provide a device of this character combining a tilting support or rack and a wheeled truck which may be quickly transformed from one to the other without detaching any of the parts.

With these and other objects in view, the invention consists in certain novel features of construction as hereinafter shown and described and then specifically pointed out in the claims, and in the drawings illustrative of the preferred embodiment of the invention:—

Figure 1 is a side elevation of the improved device arranged as a wheel truck with the outlines of a barrel thereon in horizontal position.

Fig. 2 is a similar view partly in section, with the outlines of a barrel thereon in vertical position.

Fig. 3 is a front elevation, partly in section.

Fig. 4 is a plan view of the upper or stationary frame, with the frame members in transverse section on the line 4—4 of Fig. 2.

Fig. 5 is a plan view of the lower or swinging frame in transverse section on the line 5—5 of Fig. 2.

Fig. 6 is an enlarged front elevation illustrating the construction of the locking mechanism of the swinging frame.

Fig. 7 is a transverse section on the line 7—7 of Fig. 2.

Fig. 8 is an enlarged sectional detail illustrating the construction of the trip device.

The improved device comprises coacting main frame members each formed of a section of tubing, preferably double strength steel piping, and each formed with relatively long straight portions 10, a relatively short straight portion 11, and a connecting curved portion 12. The straight portions 10 are connected by an outwardly curved brace or stay member 13, while a combined stay and pivot rod 14 extends through the frame members at the juncture of the portions 11 and 12, and secured from longitudinal displacement as by cotter pins 15 to prevent the frame members from spreading, while at the same time leaving the rod free to rotate.

Attached to the portions 11 and 12 of the main frame members is an oblong frame represented as a whole at 16 and including an inwardly curving rear member 17.

Slidably disposed in the outer open ends of the portion 10 of the main frame members is a U-shaped combined handle and extension member 18, and detachably engaged in the open ends of the shorter portions 11 of the main frame members, are angularly directed supports 19 adapted to be set to engage a barrel, indicated by dotted lines in Figs. 1 and 2, in either horizontal or vertical position.

Mounted to swing with the rod 14 is another oblong frame represented as a whole at 20, and provided with suitable caster wheels represented conventionally at 21.

The frames 16—17 and 20 are preferably of L-metal, preferably steel, as light as possible consistent with the strains to which they will be subjected when in use.

The stay member 13 and the oblong frame 16—17 are rigidly coupled to the main frame members, preferably by electric welding, while the frame member 20 is also secured to the rod 14 by electric welding.

Pivoted at 22 between ears 23 attached to the inwardly curving frame member 17, is link member 24, and pivoted at 25 to the free end of the link is a notched latch 26 engageable by its notch over the upstanding web of the rear member of the frame 20.

Extending from the bar 24 intermediate its ends is a lug 27 with a hooked extension 28, while a similar hook extension 29 is carried by the latch member 26, the hooks serving to support a spring 30 which operates to maintain the latch 26 yieldingly in engagement with the rear member of the frame 20.

Projecting laterally from the lug 27 are spacing bosses 31, having pivots 32 to swingingly receive links 33.

Attached to the lower face of the rear member of the frame 20 is a plate 34 with a pivot 35 at its inner end to receive the lower ends of the links 33.

When the bar 24 and the links 33 are in the position shown in Figs. 1, 2, 3 and 6, the main frame and its attachments will be maintained in vertical position with the frame 20 supported upon the floor, indicated at 36, thus providing an efficient combined truck and stand or rack for the barrel, either in vertical or horizontal position. The barrel may be easily moved about as will be obvious from Figs. 1 and 2.

When the barrel is to be unloaded from the support, the latch 26 is released, for instance by a suitable implement inserted between the projecting portion of the member 34 and the latch and the former used as a fulcrum to force the latch free from the bar 20 when the bar 24 with its released latch 26 and the frame 20 and links 33 can swing beneath the frame 16-17 as indicated by dotted lines in Fig. 2, with no portions extending rearwardly of the curved portions 12 of the main frame.

30 The U-shaped extension 18 is then inserted and the device tilted rearwardly on the curved portions 12 as rockers or runners, until the portions 10 of the frame bear upon the floor 36, when the barrel can be easily rolled free from the frame.

When the barrel is to be loaded, the U-shaped member 18 is detached and the device arranged in lower position and the portions 10 thrust beneath the barrel at each side 40 of the "bulge" if the barrel is to be supported vertically, as indicated in Fig. 2, or the barrel rolled upon the portions 10 if the barrel is to be supported horizontally as indicated in Fig. 1. The stops 19 are then arranged to support the barrel either horizontally or vertically, as illustrated in Figs. 1 and 2, the member 18 inserted, the main frame tilted into vertical position, and the frame 20 drawn into horizontal position, which 50 movement will cause the latch 26 to automatically couple the frame 20 to the frame 16-17, and support the main frame in vertical position.

The barrel as thus supported can then be 55 wheeled to any required position, and a draw off faucet or spigot, indicated at 37, inserted in the usual manner.

The improved device is simple in construction, can be inexpensively manufactured, and 60 operates effectually for the purposes described.

The preferred embodiment of the invention 65 is disclosed in the drawings and set forth in the specification, but it will be understood that modifications within the

scope of the claimed invention may be made in the construction without departing from the principle of the invention or sacrificing any of its advantages.

Having thus described the invention, what 70 is claimed as new, is:—

1. A device of the class described comprising a frame including relatively long longitudinally directed portions and relatively short longitudinally directed portions 75 merging into curved portions and a rigid supporting portion at right angles to the longitudinally directed portions, a base member swinging from said frame at the juncture of the curved portions and the shorter 80 longitudinal portions, means for supporting said base member at right angles to the longitudinally directed portions of the frame to support the same in vertical position, and means for detachably coupling said supporting 85 means to enable the same to be folded within the lines of the frame when not in use.

2. An apparatus of the class described comprising a frame including relatively long 90 longitudinally directed portions and relatively short longitudinally directed portions merging into curved portions and a rigid supporting portion at right angles to the longitudinally directed portions and the 95 shorter longitudinal portions, a bar swinging from one end of said frame and with a spring controlled lock device at the other end engageable with the free end of the base member, and a link device pivotally united to the ends respectively to the bar and to the base frame.

3. An apparatus of the class described comprising a frame including longitudinally directed portions merging into curved portions, and a rigid supporting portion at right angles to the longitudinally directed portions, a base member swinging from said frame, a bar swinging at one end from said frame, a latch device swinging upon said 105 bar at the other end and engageable with the swinging frame, a spring connected respectively to said bar and to said latch, and a link device pivotally united at the ends 110 respectively to the bar and to the swinging frame.

4. An apparatus of the class described comprising a frame formed of relatively long longitudinal portions and relatively short longitudinal portions connected by 120 curved portions, a rigid supporting portion connecting the longitudinally directed portions, a base member swinging from the frame at the juncture of the shorter longitudinal portions and the curved portions, and detachable supporting means between the frame and the base at its free end.

5. An apparatus of the class described comprising a frame formed of relatively long longitudinal portions and relatively 125

short longitudinal portions connected by curved portions, a rigid supporting portion connecting the longitudinally directed portions, a base member swinging at one end 5 from the frame at the juncture of the shorter longitudinal portions and the curved portions, a link swinging at one end from the frame, a latch device at the free end of the link and adapted to be detachably engaged 10 with the base.

6. An apparatus of the class described comprising a frame formed of relatively long longitudinal portions and relatively short longitudinal portions connected by 15 curved portions, a rigid supporting portion connecting the longitudinally directed portions, a base member swinging from the frame at the juncture of the shorter longitudinal portions and the curved portions, 20 detachable supporting means between the frame and the base at its free end, and a han-

dle member detachably engaging the longer longitudinal portions.

7. An apparatus of the class described comprising a frame formed of relatively long longitudinal tubular portions and relatively short longitudinal tubular portions connected by curved portions, a rigid supporting portion connecting the longitudinally directed portions, a base member 25 swinging from the frame at the juncture of the shorter longitudinal portions and the curved portions, detachable supporting means between the frame and the base at its free end, and a handle member including 30 spaced side portions detachably engaging in the free ends of the longer tubular longitudinal portions.

In testimony whereof, I affix my signature hereto.

GRANVILLE O. RHODES.
